TOBACCO CONTAINER

William Dominic Leo, Newburgh, N. Y.

Application August 23, 1937, Serial No. 160,538

1 Claim. (Cl. 229—7)

This invention relates to closures designed for containers in which tobacco, or similar pulverized or finely ground materials are packaged, the primary object of the invention being to provide a closure which may be readily and easily manipulated by the thumb of the person removing the contents of the container.

An important object of the invention is to provide a cover of a construction which will permit the contents of the container to be poured therefrom so that when used as a cover for tobacco cans the required amount of tobacco for filling a pipe or cigarette paper, may be removed, without waste or without spilling the tobacco.

With the foregoing and other objects in view, which will appear as the description proceeds, the invention resides in the combination and arrangement of parts and in the details of construction hereinafter described and claimed, it being understood that changes in the precise embodiment of the invention herein described, may be made within the scope of what is claimed, without departing from the spirit of the invention.

Referring to the drawing:

Figure 1 is a plan view of a tobacco closure constructed in accordance with the invention.

Figure 2 is a view showing the closure as moved to its open position.

Figure 3 is a longitudinal sectional view through a tobacco can equipped with the closure.

Figure 4 is a plan view of a modified form of the invention.

Figure 5 is a longitudinal sectional view through the modified form of closure.

Figure 6 is a transverse sectional view through the modified form of closure.

Referring to the drawing in detail, the reference character 5 designates a tobacco can, and the reference character 6 designates the hinged closure forming a part thereof.

This hinged closure is provided with a discharge opening 7 disposed near one end thereof, the opening 7 being normally closed by means of the sliding closure or plate 8, held in position by means of the headed member 9 that has its leg portions 10, bent laterally into engagement with the plate 8, the headed member 9 acting as a finger piece whereby the plate 8 may be operated.

The member 9 operates in the elongated opening 11 formed in the hinged closure 6, so that

sliding movement of the closure 8 will be permitted.

In the form of the invention as shown by Figure 4 of the drawing, a plate 12 is provided which plate 12 is provided with spurs 13 at its corners, adapted to be extended through the end of a container constructed of cardboard or heavy paper material, securing the plate in position.

A discharge opening 14 is formed in the plate, through which material being poured from the container, may pass. The plate 12 is also provided with an elongated opening through which the headed member 15 operates, the headed member being secured to the sliding closure 16 which operates between the flanges 17, depending from the longitudinal side edges of the plate 12.

From the foregoing it will be seen that due to the construction shown and described, I have provided a sliding closure for a container which may be readily and easily operated by the thumb of the hand holding the can, to the end that the required amount of tobacco or material to be poured, may be insured at all times.

While I have shown and described the closure as used in connection with tobacco cans, it is to be understood that the closure may be used in connection with containers used in packaging finely ground materials, such as salt, pills and pellets, cereals or the like.

It might be further stated that the material of which the container is constructed may be tin, cardboard or the like, and the size and shape of the opening covered by the closure, may be changed to meet various requirements, without departing from the spirit of the invention.

Having thus described the invention, what is claimed is:

A closure for containers having discharge openings, said closure comprising a plate secured directly under the opening and having an opening registering with the discharge opening of the container, said plate having depending flanges, a sliding closure plate of a width to extend over the entire space between the flanges, whereby the sliding closure plate is held against lateral movement, prongs extending from the first mentioned plate and adapted to be extended through the container securing the first mentioned plate in position, and a headed member for moving the sliding closure plate over the openings to regulate the discharge of material through the openings.

WILLIAM DOMINIC LEO.
